Primary Examiner—M. N. Pandozzi*Assistant Examiner*—Cynthia Underwood(74) *Attorney, Agent, or Firm*—Hogan & Hartson LLP(57) **CLAIM**

The ornamental design for a valve of a coffee maker, as shown and described.

DESCRIPTION

FIG. 1 is an environmental perspective view of a valve for a coffee maker;

FIG. 2 is a perspective view of the valve for a coffee maker;

FIG. 3 is a side view of the valve for a coffee maker;

FIG. 4 is a top view of the valve for a coffee maker;

FIG. 5 is a side view of the valve for a coffee maker; and,

FIG. 6 is a bottom view of the valve for a coffee maker.

The broken line showing the coffee maker is included for the purpose of illustrating environmental structure and forms no part of the claimed design.
